OIL DIVERTER AND DILUTION SYSTEM

George Herbert Gill, Los Angeles, Calif., assignor to The Garrett Corporation, Airesearch Manufacturing Company division, Los Angeles, Calif., a corporation of California

Application March 8, 1944, Serial No. 525,490

7 Claims. (Cl. 137—110)

1

This invention relates to lubricating systems for internal combustion engines, especially of the type used in aeronautical apparatus, and is specifically concerned with the conditioning of the lubricating oil so that adequate and efficient lubrication for the engine may be provided at all times and ready starting in cold weather is facilitated.

It is an object of the invention to render the lubricating oil, which has become viscous and difficultly movable because of cold weather, readily 10 fluid and easy of circulation, thereby to enable the engine to start without delay.

It is a further object of the invention to control the viscosity of the lubricating oil in the engine to a point where it will most effectively lubricate the engine, and to maintain the oil in such 15 condition as temperature changes are encountered.

It is still a further object of the invention to provide a simple and efficient means in which the lubricating oil is maintained constantly in a condition of desirable viscosity in an automatic manner by heat and by dilution, where necessary, due to extreme cold.

It is a further object of the invention to provide a simple arrangement for diluting the oil in the circulation system of the engine and only a portion of the oil in the source of oil supply to the end that the oil may be reduced in viscosity within a short period of time, thereby affording effective lubrication when making a cold start of the engine.

These and other objects will appear from the description in connection with the accompanying drawing, which illustrates a preferred embodiment of the invention.

Fig. 1 is a diagrammatic illustration of a lubricating system which incorporates my invention.

Fig. 2 is an enlarged sectional view of a valve means.

Fig. 3 is a plan section, taken on the line 3—3 of Fig. 2.

In a general sense, my invention includes a valve means selectively operable to control a flow of warm or hot oil through the restricted area of a reservoir of oil, the viscosity of which is high, owing to cold, thereby to effect a transfer of heat from said warm or hot oil to the cold oil, the valve means causing all the oil to flow to said reservoir and bypass the restricted area therein when all the oil is heated. In this way a small portion of the oil may be heated by and circulated through the engine until the major portion of the oil is reduced in viscosity to a degree equal to that of the small portion.

An oil circulating system is illustrated in Fig. 1 in connection with an engine and includes a pump 10 in a line 11 between the engine 12 and a source of oil supply 13 for delivering oil to the engine under pressure; a pump 14 in a line 15 for withdrawing the oil from the engine and re-

2

turning it to the source of supply, and a heat exchanger 9 of approved type. The source 13 of oil supply is shown as a reservoir in which the oil is received through the line 15. The reservoir 13 has an oil receiving chamber 16 and a compartment 17. Above the reservoir is a chamber 18, which is in communication with the oil line 15 at its upper part, and at its lower part is in communication with the compartment 17 and the oil receiving chamber 16. The compartment 17, which may be in the form of a hopper or vertical tube, extends in and to within a short distance from the bottom of the reservoir, and the open end thereof is disposed preferably immediately over the outlet 13' in the reservoir, which outlet leads to the line 11 through which the oil is withdrawn from the reservoir for circulation through the engine 12. Said compartment or tube 17 has desirably a plurality of holes 19 in the lower part thereof, and provides a path of travel for the oil, which path is restricted in cross-sectional area relation to the cross-sectional area of the reservoir and is isolated therefrom, the purpose of such isolation being to circulate and recirculate the warm oil to the engine through this restricted path until a desired degree of temperature of the oil is reached. The circulation of oil through the compartment or tube 17 causes the heat therefrom conductively and convectively to be transferred gradually to the cold or viscous oil in the chamber 16, part of which oil is gradually entrained with the warm oil circulating through the compartment 17. When the oil entering the oil inlet or chamber 18 through the line 15 is heated to a desirable temperature, its travel through the compartment or tube 17 is diverted to the main body of oil in the chamber 16, which thereupon courses through the circulation system, heretofore set out. Means for effecting this diversion of oil includes the inlet chamber 18 into which the oil is received from the line 15, and which, as stated, communicates with the chamber 16 and the compartment or tube 17. The inlet chamber 18 is provided with a plurality of openings 20 and 20' arranged for communication respectively with said compartment or tube 17 and chamber 16, such communication being controlled by the valve members 21 and 22, which are mounted on a core 23 of a solenoid 24, the armature of which is suitably supported within said chamber 18.

The solenoid 24 is in an electric circuit 25 which includes a source of energy, as a battery *a*, a main switch 26 and contact 26', a secondary switch 27 and contact 27'. Also included in said circuit 25 is a switch 28, which is normally held closed or in engagement with a contact 29 in the circuit 25 by a spring 30. When the circuit is closed by the actuation of the switches 26 and 27, the solenoid 24 is energized and the core 23

thereof moved to cause the valve member 21 to open the outlet 20 from the chamber 18, and simultaneously to close the outlet or opening 20' as shown by the solid lines in Fig. 1 and dotted lines in Fig. 2. Thereby the oil entering the chamber 18 is caused to pass through said outlet 20 directly into the compartment or tube 17, and thence into the line 11 leading to the engine. In this way warm oil from the engine is continuously recirculated to the engine. The heat of the warm oil increases during the period of circulation through the tube 17 and transfers a portion of its heat to the cold or viscous oil in the chamber 16, as a result of which the oil in the chamber is gradually entrained with the circulating oil, until all or the major portion of the oil reaches a desired temperature. At such time, the circuit 25 is interrupted, as explained hereinafter, which causes the solenoid 24 to be deenergized. Under the influence of a spring 31 the core 23 is operated to cause the valve member 21 thereof to close the outlet 20 in the chamber 18 and the valve member 22 to open the outlet 20' therein, whereby the oil entering the chamber 18 through the line 15 passes directly into the chamber 16 while circumventing the tube 17. Means for interrupting the circuit 25 includes a temperature influenced element or member 32 suitably positioned, as in a pocket 32', projecting into the chamber 18 so as to be affected by the temperature of the oil passing through the chamber 18 and disposed in operative relation to said aforementioned switch 28, whereby when said element or member 32 is caused to expand under heat influence, it moves the switch 28 away from the contact 29. Cooling of the oil will cause the thermal element 32 to contract, thereby enabling the spring 30 to engage the contact 29 and complete the circuit.

Under certain circumstances, as when starting of the engine is difficult on account of a highly viscous condition of the oil, it is desirable to reduce the oil viscosity by adding a diluent or introducing a diluent into the circulation system, and confining the dilution only to that of the oil in the tube or hopper 17. For this purpose, a suitable dilution agent is derived from a suitable source through a line 33, and transmitted through a line 34 connected to the line 11, by a motor and pump 35. The motor is in a second electric circuit 40, which is operated when the manually controlled switch 21 having a second arm 37 coupled to it by the insulating member 36, is thrown in engagement with the contact 41. This circuit 40 includes the source of energy or battery *a*, the solenoid 24 and the switch 28. By the closing of the switches 27 and 37, the solenoid 24 is energized through the contact 41, wire 39, contact 41' and wire 40', to unseat the valve member 21, thereby establishing direct communication between the chamber 18 and the compartment 17, and seating the companion valve member 22, whereby all of the oil entering through the line 15 is caused to travel from the chamber 18 to the compartment 17. Simultaneously, the motor 35 and the pump, being now in a closed circuit, are set in motion to deliver a diluent to the line 11, which, under the action of the pump 10, is caused to circulate through the engine 12, wherein a dilution of the viscous oil occurs. By the pump 14 the diluted mixture is returned to the oil inlet 18, from which it passes in the hopper or tube 17, and thence back into the circulation line. In this manner only the oil in the system and that in the compartment or hopper 17 is diluted, and the diluted oil made available im-

mediately for lubrication of the engine. When no further need exists for diluting the oil, the switches 27 and 37 are opened and the motor and pump 35 are thus cut out of the circuit, the switch 27, returning to the contact 27', then reestablishing the circuit to the solenoid 24 through the temperature sensitive switch 28. If the switch 28 is closed, the oil continues to discharge into the compartment 17. The normal procedure is to stop the engine 12 when the dilution switch 27 is turned off, thus stopping the pumps 10 and 14. The diluted oil remains in the compartment 17, lines 11 and 15, engine 12, and heat exchanger 9. When the engine is started again, the diluted oil is immediately available in the system, and as soon as the engine is turned on, the solenoid 24 is energized to keep the diluted oil flowing into the hopper 17. This action continues until the temperature rises to operate the temperature sensitive switch 28, as explained previously. When the engine is started, it is not always desirable or necessary to have the dilution motor 35 operate; therefore the switch 37 is incorporated.

I claim as my invention:

1. An oil reservoir for the lubricating system of an internal combustion engine, comprising: means defining a main storage compartment, a warm up compartment, an inlet compartment, a pair of ports affording communication between said inlet compartment and said main and warm up compartments respectively, an inlet for delivering oil into said inlet compartment, and an outlet through which the oil may leave the reservoir directly from either said main or warm up compartment; valve means in said inlet compartment, selectively operable to open one of said ports while closing the other and vice versa, whereby the inlet flow may be directed selectively either to said warm up compartment or said main compartment from said inlet compartment; and thermo-responsive means for operating said valve means positioned to be influenced by the temperature of the oil flowing through said inlet compartment.

2. An oil reservoir for the lubricating system of an internal combustion engine, comprising: means defining a main storage compartment, a warm up compartment, an inlet compartment, a pair of ports affording communication between said inlet compartment and said main and warm up compartments respectively, an inlet for delivering oil into said inlet compartment, and an outlet through which the oil may leave the reservoir from either said main or warm up compartment, said ports being coaxially arranged; a solenoid in said inlet compartment between said ports and coaxial therewith, said solenoid having an armature shiftable along the axis of said ports; a pair of valve elements carried by the respective ends of said armature and adapted to coat with the respective ports so as to close one of the ports while opening the other and vice versa; and thermo-responsive means for controlling the energization and deenergization of said solenoid, said thermo-responsive means being so located as to be influenced by the temperature of the oil flowing through said inlet chamber in such a manner as to direct the flow through said warm up compartment when the temperature of the oil is below a predetermined value and to direct the oil through said main storage compartment when the temperature is above said predetermined value.

3. An oil reservoir for the lubricating system

of an internal combustion engine, comprising: means defining a main storage compartment, a warm up compartment, an inlet compartment, a pair of ports affording communication between said inlet compartment and said main and warm up compartments respectively, an inlet for delivering oil into said inlet compartment, and an outlet through which the oil may leave the reservoir from either said main or warm up compartment, said ports being coaxially arranged; a solenoid disposed in said inlet compartment between said ports and coaxial therewith, said solenoid having an armature shiftable along the axis of said ports; a pair of valve elements carried by the respective ends of said armature and adapted to cooperate with said ports so as to close one of them while opening the other and vice versa; means yieldingly biasing said armature toward a position wherein said valve elements direct the flow from said inlet compartment through said main storage compartment; and means located so as to be responsive to the temperature of the oil at a selected point in the system for energizing said solenoid to reverse the position of said valves against the resistance of said yielding means and thereby direct the flow through said warm up compartment when the temperature of the oil is below a predetermined minimum.

4. An oil reservoir for the lubricating system of an internal combustion engine comprising: means defining a main storage compartment, a warm up compartment, an inlet compartment, a pair of axially opposed ports affording communication between said inlet compartment and said main and warm up compartments respectively, an inlet for delivering oil into said inlet compartment, and an outlet through which oil may leave the reservoir directly from either said main or warm up compartments; valve means in said inlet compartment comprising a solenoid coaxially arranged between said ports, an armature for said solenoid shiftable along the axis of said ports, and a pair of valve elements carried by the respective ends of said armature and cooperating with the respective ports, said valve means being selectively operable to open one of said ports while closing the other and vice versa, whereby the inlet flow may be directed selectively either to said warm up compartment or to said main compartment from said inlet compartment; and thermo-responsive means for operating said valve means, said thermo-responsive means being positioned to be influenced by the temperature of the oil flowing through said inlet compartment.

5. An oil reservoir for the lubricating system of an internal combustion engine, comprising: means, including walls, defining a main storage compartment, a warm up compartment, an inlet compartment, one wall of said inlet compartment having a recess formed therein, a pair of ports affording communication between said inlet compartment and said main and warm up compartments respectively, an inlet for delivering oil into said inlet compartment, and an outlet through which the oil may leave the reservoir directly from either said main or warm up compartments; valve means in said inlet compartment, selectively operable to open one of said ports while closing the other and vice versa, whereby the inlet flow may be directed selectively either to said warm up compartment or to said main compartment from said inlet compartment; and thermo-responsive means located at least in part

in the recess provided in said wall of the inlet compartment for operating said valve means.

6. An oil reservoir for the lubricating system of an internal combustion engine, comprising: means defining a main storage compartment, a warm up compartment, an inlet compartment, a pair of axially opposed ports affording communication between said inlet compartment and said main and warm up compartments respectively, an inlet for delivering oil into said inlet compartment, and an outlet through which oil may leave the reservoir directly from either said main or warm up compartments; and valve means in said inlet compartment comprising a solenoid coaxially arranged between said ports, an armature for said solenoid shiftable along the axis of said ports, and a pair of valve elements carried by the respective ends of said armature and cooperating with the respective ports, said valve means being selectively operable to open one of said ports while closing the other and vice versa, whereby the inlet flow may be directed selectively either to said warm up compartment or to said main compartment from said inlet compartment.

7. An oil reservoir for the lubricating system of an internal combustion engine, comprising: means defining a main storage compartment, a warm up compartment, an inlet compartment, a pair of opposed ports affording communication between said inlet compartment and said main and warm up compartments respectively, an inlet for delivering oil into said inlet compartment, and an outlet through which the oil may leave the reservoir directly from either said main or warm up compartments; valve means including a solenoid, an armature for said solenoid, and a pair of valve elements carried by said armature and arranged to cooperate with the respective ports, said valve means being selectively operable to open one of said ports while closing the other and vice versa, whereby the inlet flow may be directed selectively either to said warm up compartment or said main compartment from said inlet compartment, and thermo-responsive means for controlling the operation of said valve means, said thermo-responsive means being positioned so as to be influenced by the temperature of the oil flowing through said inlet compartment.
